UNITED STATES PATENT OFFICE.

CHARLES H. WELLINGTON, OF VENTURA, CALIFORNIA, ASSIGNOR TO CASEY MANUFACTURING COMPANY, OF OXNARD, CALIFORNIA, A PARTNERSHIP COMPOSED OF CHARLES H. WELLINGTON, OF VENTURA, CALIFORNIA, AND CHARLES L. HIBT, OF OXNARD, CALIFORNIA.

STARTING SWITCH.

Application filed April 5, 1923. Serial No. 629,990.

To all whom it may concern:

Be it known that I, CHARLES H. WELLINGTON, a citizen of the the United States, and resident of Ventura, in the county of Ventura and State of California, have invented new and useful Improvements in a Starting Switch, of which the following is a specification.

This invention relates to a switch mechanism for electrically connecting a single phase induction motor having a split phase starting winding to a source of electrical energy. One method of starting and bringing up to speed a single phase induction motor is to employ a starting winding of the split phase type. This split phase winding is designed only for starting and when the motor reaches full speed, it should be disconnected from the line in order to prevent 10 serve the winding against injury and to keep the motor operating efficiently.

The primary object of this invention is to provide a switch mechanism and running windings so connected that only a limited 15 current is admitted to the windings at starting. More particularly, I employ a plurality of running windings in parallel, connecting less than the total number of running windings to the line at starting, and 20 connecting all the running windings to the line when operating at full speed.

These objects together with other objects and corresponding accomplishments are obtained by means of the embodiment of my 25 invention illustrated in the accompanying drawing, in which:

Fig. 1 is a plan view of a complete mechanism adapted for connection between the line and the motor; Fig. 2 is a section as 30 seen on the line 2-2 of Fig. 1 showing the elements of the structure in elevation; Fig. 3 is a section as seen on the line 3-3 of Fig. 2; Fig. 4 is a section as seen on the line 4-4 of Fig. 1; Fig. 5 is a wiring diagram; and Fig. 6 is an end elevation of 35 the complete structure.

Referring more particularly to Fig. 5, the rotor of an induction motor is indicated by A. B and C indicate the running windings and D the split phase starting winding. For the purpose of indicating that 40 there is a difference in phase, a condenser is conventionally shown in series with the starting winding, although in practice no

condenser is employed, the induction of the 55 winding being sufficient to split the phase. Line leads from the source of electrical energy are indicated by E and F. The line lead E is connected by a conductor G to the motor windings, B, C, and D. A conductor H connects lead E to one contact of a switch J. The other contact is connected by a conductor K to one terminal of an electromagnet L. The other terminal of the 60 electromagnet L is connected by a conductor M to a contact N² of a switch, the switch being indicated generally by N. The contact N² is connected by a conductor O to the motor winding C. Contact N¹ is connected to the motor winding B. Contact N³ 65 is connected to the line lead F. Contact N⁴ is connected to one terminal of an electromagnet P. The other terminal of the electromagnet is connected by a conductor R to the motor winding D. A manually operable contact finger S is arranged to be placed in engagement with switch contacts N², N³, and N⁴. A contact finger T is arranged to engage contacts N¹, N², and N³. The contact finger T is operated by a differential 70 armature U controlled by electromagnets L and P.

Referring to the wiring diagram, assume that switch J is closed, this being its normal condition. The switch mechanism is 75 now operated to bring switch finger S into engagement with contacts N², N³, and N⁴. At this time, switch finger T is out of engagement with the switch contacts. Current now flows from the line lead F to contact N³ and through the switch finger S to contacts N² and N⁴. Current will flow from contact N² through the conductor O to the running winding C of the motor and through the conductor G to the line lead E. Current also flows from the contact N⁴ through the electromagnet P, conductor R, through the starting winding D, from the starting winding through the conductor G to the line lead E. Current will also flow 80 from the conductor N² through the conductor M, electromagnet L, conductor K, switch J, and conductor H to the line lead E. This places the running winding C and starting winding D on the line. A 85 field is produced in the stator to cause rotation of the rotor and the latter picks up speed finally attaining full speed. The mo-

tor windings admit a relatively large current when the motor is initially connected to the line. This current decreases as the speed of the rotor increases. The current through the motor starting winding D will be a minimum when the motor has reached its full speed. The energization of the electromagnet P is a minimum when the motor is at full speed due to being in series with the motor winding D. Assuming that the line voltage is constant, which is the normal condition of the line, the current passing through electromagnet L is constant, it being shunted across the line. This produces an energization of the electromagnet L which is constant, and a constant pull upon the armature U by the electromagnet L.

The normal position of the armature is that shown in Fig. 5 with the armature resting against the pole of the electromagnet P. The armature is pivoted at V between the electromagnets. When the motor reaches full speed, the pull of electromagnet P upon the armature U will be overcome by the pull of the electromagnet L upon the armature. The armature is then caused to rock so that it rests against the pole of electromagnet L. This causes the contact finger T to be moved into engagement with contact N¹, N², and N³. The effect of this is to connect the contact N¹ with the line lead F. Current then flows from the line lead F through contact N³, finger T, contact N¹, by way of conductor Q to the running winding B and then through the conductor G to the line lead E. With the contact fingers S and T in engagement with the contacts N¹, N², N³, and N⁴, running windings B and C and starting winding D are all in circuit. Contact finger S may now be disengaged. This disconnects the contact N⁴ from electrical connection with the contact N³ through the finger S and thereby disconnects it from the line lead F. Electromagnet P is deenergized and the starting winding D is disconnected. The motor now operates with the running windings B and C. The motor will continue to operate until finger T is disengaged from contacts N¹, N², and N³. This might be accomplished by pulling finger T away from the contacts against the action of electromagnet L. Another method is to deenergize the electromagnet L, which may be accomplished by opening switch J. The normal position of the armature being that shown in Fig. 5, with the electromagnet deenergized, the armature will now rock to draw the finger T away from the contacts. The operator can judge the time that this may occur either by experiments as to the time it requires for the motor to reach its full speed, the sound of the click of the contact finger T as it goes into engagement, or from

watching the motor. At this time, the finger S should be disengaged from its contact. At the time that it is desired to stop the motor, switch J is opened. It will be noted that only one running winding is in circuit when the motor is started. As the running winding initially pulls a large current, the amount of current required for the motor will be decreased by dividing the running winding and using only a portion thereof at starting, then when the motor has attained full speed throwing in the other divisional portion of the winding.

The mechanical elements whereby the above described electrical functions are accomplished will now be described. Plates of insulating material are indicated by 7 and 8. The plates are connected at one end by posts 9 and 10. At the other end bars 11 and 12 connect the plates. This forms a frame to support the elements. In Fig. 6 the bar 12 is shown broken out to better disclose the structure.

Mounted upon plate 7 is a block 14 having binding posts 15 and 16 for connection to the service leads. The service leads are brought in and connected to these posts. Mounted upon a block 17 connected to the plate 7 are binding posts 18 and 19 which are connected to spring fingers 20 and 21, best shown in Figs. 1 and 4. A roller of electrical material indicated by 22 engages the fingers 20 and 21 thereby making contact. The fingers 20 and 21 and the roller 22 correspond to the switch J shown in Fig. 5. An electrical conductor connects the binding post 16 and the post 18. The post 19 is connected by a conductor to the winding 23 of electromagnet L. The roller 22 is journalled upon an arm 24 and is insulated therefrom. The arm 24 is pivotally mounted as indicated by 25, upon a bracket 26 which is secured to the core 27 of the electromagnet L. The core 27 is of bipole type. The core and the elements mounted thereon are secured to the plate 8 by posts 28. Pivotally connected to the end of arm 24 is a rod 29 having at the end thereof a push button 30. A tension spring 13 is connected to the rod 29 and tends to hold the latter in a position such that roller 22 is maintained in engagement with fingers 20 and 21. Thus, normally the switch J is maintained closed. Pressure upon the button 30 will swing the arm 24 so as to break the contact between the roller and the fingers. This opens the switch.

Mounted upon the bar 12 and insulated therefrom are contact fingers 31, 32, 33, and 34 corresponding to the contacts N¹, N², N³, and N⁴, shown in Fig. 5. These contacts are designated as a group by the letter N in the several figures. The contacts are bent at right angles and depend from the bar 11. The ends adjacent the bar are

provided with binding posts for connection to the various electrical conductors.

One terminal of a running winding of the motor is adapted to be connected to the binding post on contact 31. Contact 32 is adapted to be connected to the corresponding terminal of the other running winding and to a terminal of a coil 23 of electromagnet L. Contact 33 is connected to binding post 15, thereby connecting it to a line lead. Contact 34 is connected by a conductor to the winding 35 of electromagnet P. A bracket 36 extends from the bar 12, and journaled between it and a foot of the bar 12 where it is connected to the plate 7 is a square shaft 37. Upstanding from the shaft 37 are fingers 38, 39, and 40. These three fingers are electrically connected and constitute in effect one finger corresponding to the finger S shown in Fig. 5. Three fingers instead of a single finger have been used for mechanical reasons. A crank arm 41 is secured to the shaft 47 for rocking the latter. It has a button 42 pivotally connected thereto and a spring 43 tending to hold it in such a position that the fingers S are out of engagement with the contacts N. In starting the motor the button 42 is pressed inwardly to bring the fingers S in engagement with the contacts N and is held in this position until the motor has reached full speed. Thereupon, pressure upon the button is released.

Journaled in the plates 7 and 8 is a square shaft 44 having upstanding therefrom fingers 45, 46, and 47 electrically connected to each other and in effect comprising one finger corresponding to the finger T shown in Fig. 5. These fingers are disposed to be rocked into engagement with the contacts N. Secured to the shaft 44 are spaced arms 48 and 49. By rocking the arms the contact fingers T may be moved into and out of engagement with the contact N. Pivotally mounted between the arms 48 and 49 is an armature 50 arranged to span the whole piece of electromagnet L. Pivotally mounted between the arms 48 and 49 on the other side of shaft 44 is an armature 51 arranged to be controlled by electromagnet P. It will be noted that the arms 48 and 49 with the electromagnet supporting them are so arranged that gravity will cause the armature 51 to rest against the pole piece of electromagnet P.

In starting the motor, button 42 is pressed inwardly and held in this position. This connects one running winding and the starting winding through the series magnet P, and also the shunt electromagnet L to the line. As soon as the motor has reached full speed, the electromagnet L overcomes the action of electromagnet P and rocks the shaft 44 bringing fingers T into engagement with contacts N. As soon as the motor has reached its full speed, as may be determined by the operator, button 42 is released, where-

upon spring 43 causes the shaft 37 to be rocked and contact fingers S disengaged from contacts N. This cuts the starting winding out of circuit and also the series magnet P. The motor will now continue to operate with the two running windings in parallel. The motor may be disconnected by pressing button 30 inwardly, which will open switch J and disconnect the shunt electromagnet L, thereby permitting the shaft 44 to rock and the fingers T to be moved out of engagement with the contacts N.

It is obvious that various mechanical and electrical changes may be made without departing from my invention. A time control check may be substituted for the series electromagnet P. However, the various changes which may be resorted to without departing from my invention will be apparent from the description and the subjoined claims.

What I claim is:

1. The combination with an induction motor having a plurality of running windings and a starting winding of a switch structure comprising a starting set of contacts connected thereto whereby when said set is closed less than all of said running windings will be connected in parallel and said starting winding will be connected in circuit, the remaining running winding being in open circuit, means to manually operate said set of starting contacts as a unit, a running set of contacts whereby to connect all of said running windings in parallel and to place said starting winding in open circuit, and a time delayed means for automatically closing said running contacts as a unit.

2. The combination with an induction motor having a plurality of running windings and a starting winding of a switch structure comprising a starting set of contacts connected thereto whereby when said set is closed less than all of said running windings will be connected in parallel and said starting winding will be connected in circuit, the remaining running winding being in an open circuit, means to manually operate said set of starting contacts as a unit, a running set of contacts whereby to connect all of said running windings in parallel and to place said starting winding in open circuit, a constant current electromagnet for closing said running contacts as a unit arranged to be placed in circuit by closure of said starting set of contacts, and means to delay closure of said running contacts.

3. The combination with an induction motor having a plurality of running windings and a starting winding of a switch structure comprising a starting set of contacts connected thereto whereby when said set is closed less than all of said running windings will be connected in parallel and said starting winding will be connected in circuit,

- circuit, the remaining running winding being in an open circuit, means to manually operate said set of starting contacts as a unit, a running set of contacts whereby to 5 connect all of said running windings in parallel and to place said starting winding in open circuit, a constant current closure electromagnet for closing said running contacts as a unit arranged to be placed in circuit 10 by closure as a unit arranged to be placed in circuit by closure of said starting set of contacts, an opening electromagnet in series with said starting winding, a differential armature for said electromagnets, and means 15 connecting said armature and said running set of contacts to operate the latter.
4. The combination with an induction motor having a plurality of running windings and a starting winding of a switch 20 structure comprising a starting set of contacts connected thereto whereby when said set is closed less than all of said running windings will be connected in parallel and said starting winding will be connected in 25 circuit, the remaining running winding being in an open circuit, means to manually operate said set of starting contacts as a unit, a running set of contacts whereby to connect all of said running windings in parallel and 30 to place said starting winding in open circuit, a constant current electromagnet for closing said running contacts as a unit arranged to be placed in circuit by closure of said starting set of contacts, means 35 to delay closure of said running contacts, and manually operable means to disconnect said electromagnet from circuit.
5. The combination with an induction motor having a plurality of running windings and a starting winding of a switch 40 structure comprising a starting set of contacts connected thereto whereby when said set is closed less than all of said running windings will be connected in parallel and 45 said starting winding will be connected in circuit, means to manually operate said set of starting contacts as a unit, a running set of contacts whereby to connect all of said running windings in parallel and to place 50 said starting winding in open circuit, a constant current closure electromagnet for closing said running contacts as a unit arranged to be placed in circuit by closure of said starting set of contacts, an opening electromagnet 55 in series with said starting winding, a differential armature for said electromagnets, means connecting said armature and said running set of contacts to operate the latter, and manually operable means to 60 disconnect said closure electromagnet from circuit.
6. The combination with a single phase induction motor having a pair of running windings and a split phase starting winding 65 of a switch structure comprising a starting 70 set of contacts connected thereto whereby when said set is closed one of said running windings and said starting winding will be connected in parallel across the line, the remaining running winding being in an open circuit, means to manually operate said set of starting contacts as a unit, a running set of contacts whereby to connect both of said running windings in parallel and to place 75 said starting winding in open circuit, and a time delayed means for closing said running contacts as a unit.
7. The combination with a single phase induction motor having a pair of running windings and a split phase starting winding 80 of a switch structure comprising a starting set of contacts connected thereto whereby when said set is closed one of said running windings and said starting winding will be connected in parallel across the line, 85 the remaining running winding being in an open circuit, means to manually operate said set of starting contacts as a unit, a running set of contacts whereby to connect both of said running windings in parallel and 90 to place said starting winding in open circuit, a constant current electromagnet for closing said running contacts as a unit arranged to be placed in circuit by closure of said starting set of contacts, and means to 95 delay closure of said running contacts.
8. The combination with a single phase induction motor having a pair of running windings and a split phase starting winding 100 of a switch structure comprising a starting set of contacts connected thereto whereby when said set is closed one of said running windings and said starting winding will be connected in parallel across the line, the remaining running winding being in an open circuit, means to manually operate said set of starting contacts as a unit, a running set of contacts whereby to connect both of said running windings in parallel and to place 105 said starting winding in open circuit, a constant current closure electromagnet for closing said running contacts as a unit arranged to be placed in circuit by closure of said starting set of contacts, an opening electromagnet in series with said starting winding, a differential armature for said electromagnets, and means connecting said armature and said running set of contacts 110 to operate the latter.
9. The combination with a single phase induction motor having a pair of running windings and a split phase starting winding 115 of a switch structure comprising an electrical connection common to each of said windings and one side of the line, a starting set of four contacts, one being connected to the other side of the line and one to each winding, a manually operable starting contact finger for engagement with said contacts whereby the line contact, a running winding 120 125
- 130

contact, and the starting winding contact are interconnected the remaining running winding being in an open circuit, a running contact finger for engagement with 5 said contacts whereby the line contact and both running winding contacts are interconnected and the starting winding contact is in an open circuit, and a time delayed means for closing said running contact 10 finger.

10. The combination with a single phase induction motor having a pair of running windings and a split phase starting winding of a switch structure comprising an 15 electrical connection common to each of said windings and one side of the line, a starting set of four contacts, one being connected to the other side of the line and one to each winding, a manually operable starting contact finger for engagement with said contacts whereby the line contact, a running winding contact and the starting winding contact are interconnected, the remaining running winding being in an open 20 circuit, a running contact finger for engagement with said contacts whereby the line contact and both running winding contacts are interconnected and the starting winding contact is in an open circuit, a constant 25 current closure electromagnet for closing said running contact finger arranged to be placed in circuit by closure of said starting contact finger, an opening electromagnet in series with said starting winding, a differential armature for said elec- 30

tromagnets, and means connecting said armature and said running contact finger to operate the latter.

11. The combination with a single phase induction motor having a pair of running windings and a split phase starting winding of a switch structure comprising an electrical connection common to each of said windings and one side of the line, a starting set of four contacts, one being connected to 40 the other side of the line and one to each winding, a manually operable starting contact finger for engagement with said contacts whereby the line contact, a running winding contact and the starting winding contact are interconnected, the remaining running winding being in an open circuit, a running contact finger for engagement with said contacts are interconnected and the starting winding contact is in an open 45 circuit, a constant current closure electromagnet for closing said running contact finger arranged to be placed in circuit by closure of said starting contact finger, an opening electromagnet in series with said starting winding, a differential armature for said electromagnets, means connecting said armature and said running contact finger to operate the latter, and manually operable means to open the circuit includ- 50

ing said closure electromagnet.

In witness that I claim the foregoing I

have hereunto subscribed my name this 29th

day of March, 1923.

CHARLES H. WELLINGTON.
